CONVERTIBLE ARTICLE OF FURNITURE

Warwick Mayo and Elbridge E. Nock, Jr., Norfolk, Va., assignors to Norfolk Mattress Company, Norfolk, Va.

Application November 22, 1938, Serial No. 241,850

6 Claims. (Cl. 5—44)

This invention relates to a convertible article of furniture and more particularly to an article of furniture commonly known as a studio couch.

An object of this invention is to provide an improved couch and having as elements thereof a stationary and an extendable frame structure whereby the movement of the said extensible frame is made easy so that one person can readily move the extensible frame to an extended position.

Another object of this invention is to provide in a couch structure of this kind connected end members or arm rests so that if desired either one of the arm rests may be rocked in order to extend the extensible frame from or to retract it to a telescoping position relative to the stationary frame.

A further object of this invention is to provide an improved supporting means for movably supporting the extensible frame in order that it may be readily moved to an extended position.

A still further object of this invention is to provide in a couch structure of this kind means whereby the extensible frame will be raised to a position out of engagement with the floor when the extensible frame is in a retracted position.

A further object of this invention is to provide in a structure of this kind means whereby the elevating means for the extensible frame will be disposed in a position for engagement with the elevating structure upon retraction of the extensible frame.

A further object of this invention is to provide an improved connection between the extensible frame and the operator therefor so that the operator may have a limited movement relative to the extensible frame in order not only to facilitate the movement of the extensible frame but also to position the back of the couch structure in the desired upright position.

With the foregoing and other objects in view, the invention consists of the novel construction, combination and arrangement of parts as will be more specifically referred to and as are illustrated in the accompanying drawings wherein is shown an embodiment of the invention, but it is to be understood that changes, variations and modifications may be resorted to which fall within the scope of the invention as claimed.

Figure 1 is a detail bottom plan of a couch frame structure, when retracted, constructed according to an embodiment of this invention.

Figure 2 is a detail front elevation of the couch structure.

Figure 3 is a detail top plan partly broken away of the couch structure in extended position,

Figure 4 is a detail end elevation of the couch showing in dotted lines the positions of the two frames of the couch structure when the latter is 5 in extended position,

Figure 5 is a sectional view taken transversely through the couch structure showing in dotted lines the relative positions of the parts when in extended position,

Figure 6 is a fragmentary enlarged side elevation of the supporting means between the extensible frame and the end or arm rest,

Figure 7 is a fragmentary sectional view taken on the line 7—7 of Figure 6,

Figure 8 is a enlarged fragmentary sectional view taken on the line 8—8 of Figure 1,

Figure 9 is a enlarged fragmentary sectional view taken on the line 9—9 of Figure 10,

Figure 10 is a sectional view taken on the line 10—10 of Figure 9,

Figure 11 is a section on line 11—11, Figure 3, illustrating the form and arrangement of a combined pusher and connecting member,

Figure 12 is a section on line 12—12, Figure 3, 25 and

Figure 13 is a fragmentary view in plan of the form of shiftable supporting device for a track rail and showing the arrangement of the device with respect to an end rail of the stationary 30 frame.

Referring to the drawings, the reference characters 15 and 16 designate generally a pair of frames. The frame 15 is stationary and the frame 16 movable, that is to say frame 16 is extensible with respect to frame 15. When frame 16 is retracted it is disposed in telescopic relation with respect to frame 15.

The frame 15 includes front and rear angle bars or rails 17 and 18 which are connected together by end rails or bars 19 and 20, a brace member 21 connects an end rail 19 with a rear rail 18 and a bracing member 22 connects the rear rail 18 with the end rail 20. Front and rear supporting legs 23 are secured to the frame 15 45 by bracing members 24, these latter extend upwardly from the legs 23 to the rails 17 and 18. Each leg 23 is provided at the lower end thereof with a yieldable foot 25.

The extensible frame 16 comprises front and 50 rear rails or bars 26 and 27 respectively which are connected together by end members 28. Arranged below the top of frame 16 and inwardly of each end member 28, as well as being connected with the rails 26, 27 is a rail or track 29 55

in the form of an angle bar having one leg 30 thereof fixed to the inner side of the end member 28 and the other leg 31 thereof extending right angularly inwardly and providing a track the 5 purpose for which will be hereinafter described. The frame 16 is provided with front and rear supporting legs 32 having rollers 33 at the lower ends thereof. When frame 16 is in extended position all four rollers 33 are positioned in contact with 10 the floor, but when it is in retracted position, all four of the rollers 33 are in elevated or raised position as shown in Figure 5 in full lines.

The stationary frame member 15 supports forwardly of the front thereof a pair of spaced aligned rollers 35. Each roller 35 is mounted in a horizontally disposed yoke-shaped carrier 39 (Figure 9). Positioned against the outer sides of the vertical legs and below the horizontal legs of the end rails 19, 20 are forwardly extending 20 downwardly inclined oppositely disposed bars 36 having their forward ends formed with outwardly directed extensions 37 disposed at right angles to the remaining portion of such bars 36. The extensions 37 are positioned forwardly of the front rail 17 of frame 15 and extend under the tracks 29. The carriers 39 are arranged against the forward faces of (Figure 9) and are pivotally connected to the extensions 37, as at 38. The carriers 39 are curved upwardly and the rollers 35 25 are revolvably mounted in the upper ends thereof. The carriers are disposed under the tracks 29 by the extensions. The end rails 19 and 20 of the frame 15 are provided in their vertical legs with elongated slots 40 adjacent the forward ends of 30 such rails. The slots 40 are disposed lengthwise of rails 19, 20. The bars 36 are movably secured to the end rails 19, 20 by spaced headed members 41 fixed to the bars 36 and slidably mounted in the slots 40, and in this connection attention is 35 directed to Figure 9, which discloses the arrangement of one of the bars 36 with respect to the rail 19. When the extensible frame 16 is moved to retracted position the front rail 26 thereof engages the rollers 35 and forces the bars 36 to their innermost position relative to the slots 40. When the frame 16 is in an extended position, relative to the frame 15, the bars 36 are moved forwardly by the engagement with the extensions 37 of the horizontal legs of the depending angular shaped 40 members 42 which are fixed to the front of the vertical leg of the rear rail 27 of the frame 16 at the end terminal portions of such vertical leg. The tracks 29 are to travel on the rollers 35 for the purpose of elevating frame 16. The extensible 45 movement of the frame 16 relative to the frame 15 is limited by means of the members 42 coacting with the extensions 37. The rollers, carriers and bars 36 form what may be termed combined supporting and guiding devices for the tracks. The members 42 constitute combined pushers and connectors as they act to push said devices forwardly and connect the frames together when the frame 16 is extended relative to frame 15.

60 The extensible frame 16 is locked in retracted position by a latch member 43 which is preferably mounted on a pivot 44 carried by an angle-bar 45 secured to the inner side of the front rail 26. The latch or locking member 43 as shown in Figure 8 is adapted to engage over the top of the front rail 17 of the stationary frame 15, and may be raised to a released position by means of a depending arm 46 having a horizontal extension 47 which provides an operating handle for the 65 latch member 43 projecting slightly below the

lower edge of the front rail 26 at substantially the longitudinal center of this member 26.

A pair of end members 48 and 49 are disposed one at each end of the extensible frame 16 being positioned in spaced relation to the frame 16. 5 These end members 48 and 49 are of identical construction and each end member comprises an upper bar 50, a lower horizontally disposed bar 51 and a connecting bar 52 which in the present instance is formed integral with the two bars 50 and 10 51. In the present instance the bars 50, 51 and 52 are formed from a tubular member which is bent in substantially U-shape with the bight of the members at the forward side of the couch. The upper rail or bar member 50 comprises an arm rest supporting member on which an arm rest 53 in the form of a piece of wood or suitable means is secured in any suitable manner. A longitudinally extending connecting bar 54 extends 15 along the length of the frame structure comprising the two frames 15 and 16 being normally disposed in an elevated position and along the upper edge of a back wall structure. The bar 54 has arcuate extensions 55 at each end which extend downwardly and are continued by a relatively straight extension 56 which is integral with the lower bar 51. The upper bar or rail 50 has the rear end thereof fixedly secured to the extension 56 by welding or the like so that the two 20 end members 48 and 49 are formed integral with the connecting bar 54 and are adapted to rock simultaneously with the rocking of the connecting member 54 as will be hereinafter described. An intermediate connecting member 57 connects the upper bar 50 with the lower bar 51 at a point intermediate the front member 52 and the vertical extension 56. An upwardly extending bar or post 58 is attached as by a bolt 59 to an end frame member 28 and this bar or post 58 is adapted to have a limited rocking movement on the bolt 59. The bar or post 58 is limited in its rocking movement by means of a pair of spaced apart headed members 61 and 62 which are secured to the end frame member 28 through slots 63 and 64 respectively formed in the bar or post 58. The upper end portion of the post 58 supports the end member 48 by providing a pivot 65 which engages through the post 58 and the connecting bar 57, and preferably spacing members 66 are interposed between the post 58 and the connecting bar 57 so as to space the post 58 a desired distance from the connecting bar 57. A pair of stop members 67 are provided and which are of angular form to form a vertical and a horizontal leg. The vertical legs of the members 67 are secured to the end rails of the frame 16 and the horizontal legs are disposed outwardly with respect to the lower ends of the vertical legs and arranged in the path of the swing of the lower bars 51 so as to prevent the end members 48, 49 from rocking in one direction, this direction being a counterclockwise direction as viewed in Figure 4.

A rear or back member 69 is pivotably secured at a point upwardly from the lower end thereof to the stationary frame 15 by means of a pivot 70 and the upper end of the back wall structure 69 is pivotably secured to the horizontal connecting bar 54 by means of a pair of U-shaped straps 71 secured as by fastening devices 72 to the back member 69. This back member 69 is a combined back for the retracted couch and a top for the stationary frame member when the couch is in extended position. The position of the back member 69 when the couch is in extended posi- 75

tion is substantially horizontal as shown by dotted lines in Figures 4 and 5.

- The frame 16 is adapted to have a cushioning body 74 on the upper side thereof and a removable cushion 75 is adapted to engage on this lower cushion 74 when the couch is in retracted position. When in extended position, the cushion 75 is adapted to engage on the horizontal back member 69 as shown in dotted lines in Figure 4.
- 10 In this latter position the upper surfaces of the two cushion members 74 and 75 will be substantially coplanar.

In the use and operation of this couch structure when the device is in retracted position the extensible frame 16 will be telescoped about the stationary frame 15 as shown in Figure 1. In the event it is desired to form this couch structure into a double bed the latch member 43 is raised from engagement with the bar 17 to release the extensible frame from the stationary frame, after which the connecting bar 52 of an end member 48 or 49 is pulled forwardly and upwardly on its pivot 65. The upward movement of the end member 48 or 49 is in a clockwise direction. On the starting of the clockwise movement of the end member 48 or 49, as the back 69 is pivotally connected at its upper end to bar 54 of end member 48 or 49, the back 69 is shifted out of a direct vertical line and affords a leverage 20 for separating the frames. The movement aforesaid of the end member 48 or 49, due to the points of the pivotal connections 71 between it and the back 69 will provide for the latter moving in an anti-clockwise or forward direction on its pivot 30 to assume its dotted line position (Figures 4 and 5) after the extensible frame has been shifted from the stationary frame to the desired extent. As the extensible frame is moving forwardly relative to the stationary frame the rails 29 ride over 35 the rollers 35. The rails 29 after the frame 16 has been moved a slight distance will be spaced above the front rollers 35 and at this time the front rollers 33 will be in contact with the floor. Further outward shifting of the frame 16 caused 40 by a further clockwise movement of the end member 48 or 49 will cause frame 16 to be placed in the dotted line positions Figures 4 and 5. Just before the frame 16 reaches the extent of its forward shifted position, the extensions 37 will 45 contact with the depending members 42 whereby the rollers 35 will be extended forwardly beneath the rails or tracks 29, and at this time the tracks 29 will be substantially out of contact with the rollers 35.

50 When it is desired to shift the frame 16 from extended position to telescopic position with respect to the frame 15, the extension 56 of the end member 48 or 49, which is now disposed at the front of the latter is pushed rearwardly with a 55 downward pull thereon whereby the end member will be revolved on its pivot in an anti-clockwise direction resulting in the back 69 moving clockwise on its pivot 70. The end member is revolved anti-clockwise to an extent to provide for the end 60 member and back 69 to assume the full line positions, Figures 4 and 5. As the frame 16 moves rearwardly the rails 29 will ride up on the rollers 35 to its telescopic position with respect to frame 15, and when in such position the rollers 33 of 65 the frame 16 will be elevated off the floor.

When the couch structure is in a retracted position the vertical position of the back member 69 may be regulated by means of the swing-ing post 58 so that the back member 69 may be disposed in either a true vertical position or a

forwardly inclined position or a slightly rearwardly inclined position. It will be understood that the usual loose cushions may also be used with this couch structure such cushions being placed in an upright position along the back 5 member 69 and on top of the removable cushion member 75. For convenience of illustration these loose cushions have not been shown in the drawings.

What we claim is:

1. In a convertible couch structure comprising a stationary frame, an extensible frame, a pair of inwardly projecting track members carried by said extensible frame and disposed on an inclination to the horizontal, legs carried by said extensible frame, rollers carried by said legs, a pair of slide bars, means slidably securing said bars to said stationary frame, a roller carried by each bar engageable with the lower face of a track member whereby to elevate said extensible frame 20 upon retraction thereof, a pair of looped end members disposed one at each end of said extensible frame, means pivotally securing said end members to said extensible frame, a connecting bar connecting said end members together, a 25 back structure, means pivotally securing said back structure to said stationary frame, means pivotally securing said back structure to said connecting bar, and releasable latch means carried by said extensible frame and engageable with 30 said stationary frame member to releasably lock said extensible frame member in retracted position.

2. A convertible couch structure comprising a stationary frame, an extensible frame, means slidably mounting said extensible frame on said stationary frame, a pair of end members disposed one at each end of said extensible frame member, posts pivotally connected to the ends of the extensible frame for pivotally suspending said 35 end members between their tops and bottoms, means for limiting the extent of the pivoting movement of said posts in opposite directions, means rigidly connecting said end members together, a substantially flat rear wall structure, means pivotally securing said rear wall structure to said stationary frame, and means pivotally securing said rear wall structure to said connecting means, said rear wall structure being engageable with the upper side of said stationary frame 40 when said extensible frame is in extended position to thereby constitute a top for said stationary frame.

3. In a convertible article of furniture of that type including a stationary frame, the combination of a movable frame for normally disposing in telescopic relation with respect to the stationary frame and adapted to be moved in directions respectively from normal position to seat on the floor and to normal position to encompass the 50 stationary frame, said movable frame being formed of a front rail, a rear rail, a pair of end rails and parallel track rails inclining downwardly and forwardly arranged below its top and inwardly of said end rails, spaced parallel oppositely shiftable combined supporting and guiding devices including revoluble parts forwardly of the front of the stationary frame for correlation with the lower faces of said track rails to provide for the track rails elevating the movable frame 55 as the latter is shifted to telescopic relation with respect to the stationary frame, said devices arranged in the rearward path of and shifted rearwardly by said front rail on the moving of the movable frame to telescopic position with 60 65 70 75

respect to the movable frame, means for shiftably connecting said devices to the ends of the stationary frame and for limiting the extent of the shift of said devices in opposite directions, and 5 depending means carried by said rear rail and coacting with said devices for limiting the extent of the movement of the movable frame from its normal position, for shifting forwardly said devices to position said revoluble parts under the 10 track rails and correlating with said devices for connecting the frames together when the movable frame is extended.

4. In a convertible article of furniture a stationary frame, a movable frame for normally disposing in telescopic relation with respect to the stationary frame and movable in directions respectively from normal position to be arranged parallel to the front of the stationary frame and to normal position to encompass the stationary 20 frame, releasable means for securing the movable frame in telescopic relation with respect to the stationary frame, upstanding pivoting supports connected to and projecting above the ends of the movable frame, means for limiting the 25 extent of the pivoting movement of said supports in opposite directions, upstanding skeleton end structures each including an arm rest and a vertical brace intermediate its ends, said braces being pivotally suspended intermediate their ends on 30 said supports to provide for the turning of said structures, a bar connecting the rear end of one structure to the rear end of the other structure, a vertically disposed back hinged adjacent its lower end to the rear of the stationary frame, 35 means pivotally connecting the upper end of said back to said bar to provide for said structures moving said back from vertical to horizontal position onto the top of the stationary frame when the movable frame is moved from normal 40 position and for moving said back from horizontal to vertical position when the movable frame is moved to normal position.

5. In a convertible article of furniture a stationary frame, a movable frame for normally disposing in telescopic relation with respect to the stationary frame and movable in directions respectively from normal position to be arranged parallel to the front of the stationary frame and to normal position to encompass the stationary 50 frame, releasable means for securing the movable frame in telescopic relation with respect to the stationary frame, upstanding pivoting supports connected to and projecting above the ends of the movable frame, means for limiting the 55 extent of the pivoting movement of said supports in opposite directions, upstanding skeleton end

structures each including an arm rest and a vertical brace intermediate its ends, said braces being pivotally suspended intermediate their ends on the supports to provide for the turning of said structures, a bar connecting the rear end of one 5 structure to the rear end of the other structure, a vertically disposed back hinged adjacent its lower end to the rear of the stationary frame, means pivotally connecting the upper end of said back to said bar to provide for said structures moving said back from vertical to horizontal position onto the top of the stationary frame when the movable frame is moved from normal position and for moving said back from horizontal to vertical position when the movable frame 10 is moved to normal position, and means carried by the ends of the movable frame arresting the turning movement of said end structures in one direction when said movable frame is moved to normal position.

6. A convertible couch comprising a stationary frame, an extensible frame normally disposed in telescopic relation with respect to said stationary frame, said extensible frame including a pair of downwardly and forwardly inclined parallel 25 tracks disposed inwardly of the ends and below the top thereof, a pair of retractable and extendible parallel rollers arranged forwardly of the front of the stationary frame, positioned below the tracks, normally in retracted position and 30 providing when extended for correlation with said tracks to elevate the extensible frame when the latter is moved from extended to telescopic position, a pair of oppositely disposed, oppositely 35 shiftable supporting members inclining downwardly and forwardly having their outer ends formed with outwardly directed extensions, means for slidably connecting said members to the ends of the stationary frame and for limiting the extent of the shifting movement of said members 40 in opposite directions, upturned carriers revolvably supporting said rollers, connected to said extensions and bodily moving with said members, means carried by the extensible frame and engaging with the flanges of said members, 45 when such frame is moved to extended position to shift said members forwardly to extend the rollers under the tracks and to connect said frames together, and said extensible frame including a front rail engageable with the rollers, 50 when such frame is moved to telescopic position to shift the rollers and said members to retracted position.

WARWICK MAYO.
